SHIELD FOR FURNACE TUBES

George Potts, Hillside, N. J., assignor to Standard
Oil Development Company, a corporation of
Delaware

Application May 5, 1931, Serial No. 535,195

3 Claims. (Cl. 196—116)

This invention relates to improvements in means for protecting the tubes of a tube still, tubular reaction chamber, or the like, from the adverse effect of excessive radiant heat. In a 5 preferred embodiment of the invention the tubes are protected by placing over them a shielding structure, preferably of the nature of I-beams, in such manner as to intercept the radiant heat. A further object of the invention is to secure 10 the stated protection without substantially impairing the heat input from convection.

The invention will be fully understood from the following description, read in connection with the accompanying drawing, in which

15 Fig. 1 is a vertical section through a furnace in which the upper bank of tubes in the convection section is protected by I-beams,

Fig. 2 is a longitudinal section taken on the line 2—2 of Fig. 1, and

20 Figs. 3 and 4 are enlarged perspective views of tubes and alternative forms of protective means.

Referring first to Figs. 1 and 2, reference numeral 1 denotes a furnace setting which may be of any suitable kind. Typical installations to 25 which this invention are applicable include cracking coils, high temperature tube stills, tubular hydrogenation units and the like. In general the invention is applicable wherever extremely high temperatures are generated and applied to 30 liquids or gases flowing through tubes. In the setting illustrated there is the usual bank of tubes 2 arranged in the radiant heat section 3 of the furnace 1. A bank of tubes 4 is installed in a chamber 5 which receives the hot combustion 35 gases from chamber 3 through the flue 6.

The upper wall 7 of chamber 5 may be heated to incandescence by the combustion gases. The heat from this wall is radiated downwardly and would cause the tubes in the upper row of bank 40 4 to reach too high a temperature. This is prevented by placing over these upper tubes a series of metallic protecting structures which are most conveniently in the form of I-beams 8. These I-beams are supported at several points intermediate their ends by hangers 9, which pass through the top of the chamber 5. The ends of the I-beams are received in openings in the side walls of chamber 5, and these openings are filled with asbestos wall 51 or other similar material 45 which will permit the I-beam to expand and contract.

In order to increase the protective action of the structure described it is preferred to place a heat insulating material 8' in the upper portion of 50 each I-beam. The channeled structure provided

by such beams is convenient but it will be understood that any other equivalent trough-like arrangement may be used for the same purpose. A variety of heat insulating materials may be used. Fragments of fire-brick, powdered clay or the like are suitable.

While the protective means have been illustrated only in connection with the top row of tubes, it is obvious that other tubes could be similarly protected if desirable. Ordinarily the 10 top row is the only one which is likely to receive excessive heat radiation. With the construction described it is possible to obtain all the desired heating effect by convection without overheating the tubes by radiation. It will be observed that 15 the combustion gases pass freely around all the tubes in the convection section. I am aware that beams have been used adjacent tubes to transmit radiant heat thereto and obstruct convection heat. The present invention has an opposite 20 function, as described.

In Fig. 3 an alternative form of tube shield is illustrated. This comprises a flat metallic bar 10 carrying on its upper surface a thick lagging 11 of heat insulating material. The device shown 25 in Fig. 4 is a trough-like metallic member 12 which may be filled with clay 12' or the like.

Various means have been proposed heretofore for preventing radiation from the upper wall or arch of the furnace but such means have not 30 given uniformly satisfactory service in connection with very high temperature operations, for example where the temperature of the convection section is 1800° F. or more. In such situations the shielding device of the present invention gives 35 ample protection without decreasing the efficiency of the furnace.

Various changes and alternative arrangements may be made within the scope of the appended claims in which it is my intention to claim all 40 novelty inherent in the invention as broadly as the prior art permits.

I claim:

1. A high temperature furnace comprising a radiant heat section and a convection heat section, tubes in both said sections, means for protecting the upper tubes in the convection section from radiant heat, said means comprising a shielding element arranged between each of the upper tubes and the adjacent radiant surface in 50 the convection section, and heat insulating material carried by each of said shielding elements.

2. The improvement in the process of destructive hydrogenation of carbonaceous materials, which comprises passing hot gases into a cham- 55

ber adjacent an arch in the chamber which throws out radiant heat, passing the carbonaceous materials in the presence of hydrogen through spaced rows of tubes, and independently shielding each of the tubes adjoining the arch from the radiant heat of the arch while permitting free passage of gases to the tubes.

3. In combination with furnace tubes arranged adjacent to a source of radiant heat, a protective structure adapted to decrease the transmission of radiant heat to the tubes, said structure comprising

5 a plurality of shielding elements in the form of I-beams placed on their sides so as to form an upper channel, heat insulating material in said channels, means for suspending the I-beams at points intermediate their ends so that they run parallel with and overlie the respective tubes between the same and the source of radiant heat, and means for mounting the I-beams for expansible movement at their ends.
